UNITED STATES PATENT OFFICE.

HUGH J. KEENAN, OF JACKSON, MICHIGAN, ASSIGNOR OF TWO-THIRDS TO CHARLES M. BRAUND AND LOUIS R. BRAUND, BOTH OF JACKSON, MICHIGAN.

VENDING-MACHINE.

1,091,066.

Specification of Letters Patent. Patented Mar. 24, 1914.

Application filed July 17, 1913. Serial No. 779,502.

To all whom it may concern:

Be it known that I, HUGH J. KEENAN, a citizen of the United States, residing at the city of Jackson, county of Jackson, State of Michigan, have invented certain new and useful Improvements in Vending-Machines, of which the following is a specification.

This invention relates to improvements in vending machines.

10 The main objects of this invention are: First, to provide in a vending machine an improved coin controlled actuating mechanism. Second, to provide in a vending machine an improved coin released locking mechanism. Third, to provide an improved vending machine, which is comparatively simple in structure, and one which is not likely to get out of repair in use.

Further objects and objects relating to details and economies of structure and operation will definitely appear from the detailed description to follow.

I accomplish the objects of my invention by the devices and means described in the following specification.

The invention is clearly defined and pointed out in the claims.

30 A structure which is a preferred embodiment of my invention is clearly illustrated in the accompanying drawing forming a part of this specification, in which:

Figure I is a front perspective view of a vending machine embodying the features of my invention. Fig. II is a detail vertical section on a line corresponding to line 2—2 of Fig. III. Fig. III is a detail horizontal section on a line corresponding to line 3—3 of Fig. II. Fig. IV is an enlarged detail vertical section centrally through the coin holder on a line corresponding to line 4—4 of Fig. III. Fig. V is an enlarged detail vertical section on a line corresponding to line 5—5 of Figs. III and IV. Fig. VI is a detail vertical section showing the coin holder 45 and its locking pawls on a line corresponding to line 6—6 of Figs. III and V. Fig. VII is a detail section on a line corresponding to line 7—7 of Fig. I; showing details of the magazine coin chute and its closure.

50 Fig. VIII is a front elevation of the coin holder and coin chute, the lower end of the coin chute and the supporting bar 10 being shown in vertical section. Fig. IX is a perspective view of the base section of the casing.

In the drawings similar reference characters refer to similar parts throughout the several views, and the sectional views are taken looking in the direction of the little arrows at the ends of the section lines.

60 Referring to the drawing the casing comprises a base section 1, top section 2, the top section hinged to the base section at 3, and being retained in its closed position by the lock 4. A discharge opening 5 is formed in the front side of the base section. The base section is provided with a suitable pedestal 6. The casing is cylindrical to receive the cylindrical magazine, as shown in Fig. II. The magazine comprises a wheel-like body 70 portion 7 having a journal 8, supported by supporting bars 9 and 10. These supporting bars 9 and 10 engage the rests or supports 11, on the base section of the casing so that the magazine is removably supported therein. The magazine is provided with a series of peripheral pockets 12, secured on the body portion 7 of the magazine, the pockets being formed of sheet metal as shown. These pockets are open at their ends and adapted 75 to be brought successively into register with the discharge opening 5 of the casing.

75 The structure illustrated is designed by me as a vending machine for packages of tobacco, the pockets being of such size that 80 the packages are loosely held therein.

85 The magazine casing is but slightly larger than the magazine so that the peripheral wall of the casing holds the packages in the pockets; all of the pockets being closed except the one opposite the discharge opening 5.

90 A coin holder 14 is journaled at 15 on the supporting bar 10. This coin holder is provided with a plurality of peripheral pockets 16, into which the coins drop from the coin chute 17, the casing being provided with an opening 18 adapted to receive the end of the chute.

100 In the structure illustrated the coin holder is provided with a peripheral groove 19, the coin pockets being formed by opposed notches in the walls of this groove. The front walls 20 of the notches are preferably in radial planes, the rear walls 21 being inclined rearwardly to provide flaring pockets so that the coins will drop into the same more readily.

105 The coin holder is provided with a central opening 22, and with radial slots 23, con- 110

necting the pockets with this opening 22, the front walls of the slots being in the same plane as the front walls of the pockets. On one side of the coin holder is a gear or pinion 24, which is arranged in mesh with an internal gear 25, secured to the side of the magazine as shown in Figs. II and III. On its inner side the coin holder 14 is provided with ratchet teeth 26, the teeth being 10 formed by notches 27, in the side of the coin holder:—see Fig. VI.

The coin holder is locked against rotation in either direction by the pawls 28 and 29, which are mounted in a crossed relation on 15 a pivot 30, common to both. These pawls have laterally offset engaging portions 31. The teeth 26 are spaced so that the coin holder has a limited movement while the pawls are engaged. To actuate the pawls in 20 unison the links 32 are provided, which are connected with the upper ends of the pawls by the pivots 33 and the links are connected to each other by the pivot 34. The pivot 34 projects into a guide slot 35 on the 25 bracket 36, on which the pawls are mounted. The pawl 28 is provided with a cam 28' with which the coin 37 engages during the initial movement of the coin holder, and owing to the link connection of the pawls 30 as described, they are both disengaged through the coin as a connecting member. A plunger 38 is mounted to reciprocate in the plunger support 39. One end of the support 39 is mounted on the journal 8 and 35 the other is supported by the pivot 41. The actuating lever 40 is pivoted at 41 and slotted at 42 to receive the pin 43 on the plunger. On the lower end of the lever 40 is a weight 44 by means of which the parts 40 are returned to their initial position. The actuating rod or link 45 is connected with the upper arm of the lever by the pivot 46, its outer end being arranged through the casing as shown in Fig. II. A suitable 45 finger piece 47 is provided for the link. The end 48 of the plunger reciprocates in the groove of the coin holder so that it engages the coin 37 centrally as is shown in Fig. IV.

50 In the event of a coin not dropping into the upright position shown in Fig. 4, the outwardly flared pockets effectively receive the same, and the coins are righted or swung into engagement with the front walls of the 55 pockets when the plunger is actuated. The limited movement of the coin holder permitted by the pawls allows the coin to engage the cam 28' and lift the pawls from their engaged position. The continued stroke of 60 the plunger rotates the coin holder one step and through the connections described the magazine is rotated one step, bringing the succeeding pocket into register with the discharge opening 5. As the coin holder ro-

tates the coins are discharged into a suitable 65 receptacle, not shown.

In order that coins below a predetermined size shall not be effective for actuating the machine, the slots 23 are of such size as to permit such coins to drop from the pockets 70 and be discharged through the central opening 22 of the coin holder.

The machine illustrated is designed to be actuated by 5¢ pieces, and pennies and dimes would not be effective, but would drop from 75 the coin holder.

If desired, means for conveying and discharging such coins to the outside of the casing could be provided. I have not illustrated such means herein.

80 In order to prevent the introduction of coins when the magazine is empty a slide closure 49 is provided, the same being mounted in a housing 50 above the coin chute opening. The closure 49 is provided 85 with an inturned end 51, while the magazine has a projection 52 which engages the closure upon the actuation which completed the revolution of the magazine, closing the coin chute.

90 My improved vending machine is quite simple and economical in structure and it is at the same time positive in its operation and not likely to get out of repair.

I have not attempted to illustrate or describe certain structural modifications which I contemplate as I believe the disclosure made will enable those skilled in the art to which this invention relates, to embody or adapt the same as may be deemed desirable.

95 Having thus described my invention, what I claim as new and desire to secure by Letters Patent is:

100 1. In a vending machine, in combination with a casing, a rotatable magazine, an internal gear connected to said magazine to rotate therewith, a cylindrical coin holder having a series of coin pockets, a gear on one side of said coin holder meshing with said internal gear on said magazine, spaced 105 ratchet teeth on the other side of said coin holder, a pair of pawls coacting therewith, said pawls being mounted in a crossed relation on a pivot common to both and being adapted to simultaneously engage the teeth 110 of the coin holder ratchet, whereby the coin holder is held against rotation in either direction, the ratchet teeth being spaced to permit a limited movement of the coin holder while the pawls are engaged therewith, a pair of links pivotally mounted on the upper ends of the pawls and pivotally connected to each other, a guide slot with 115 which the pivot connecting the links engages, a cam disposed on one of said pawls to be engaged by a coin in the coin holder when the holder is rotated, a plunger arranged to engage a coin held by the coin 120 125

holder when the plunger is actuated, and means for actuating the plunger, the coin constituting a connector between the plunger and holder and engaging the said cam on said pawl whereby the pawls are released during the initial movement of the coin holder.

2. In a vending machine, in combination with a casing, a magazine, a cylindrical rotatable coin holder having a series of peripheral coin pockets, said coin holder being geared to said magazine, spaced ratchet teeth on said coin holder, a pair of pawls coacting therewith, said pawls being mounted in a crossed relation on a pivot common to both and being adapted to simultaneously engage the teeth of the coin holder ratchet, whereby the coin holder is held against rotation in either direction, the ratchet teeth being spaced to permit a limited movement of the coin holder while the pawls are engaged therewith, a pair of links pivotally mounted on the upper ends of the pawls and pivotally connected to each other, a guide slot with which the pivot connecting the links engages, a cam disposed on one of said pawls to be engaged by a coin in the coin holder when the holder is rotated, a plunger arranged to engage a coin held by the coin holder when the plunger is actuated, and means for actuating the plunger, the coin constituting a connector between the plunger and holder and engaging the said cam on said pawl whereby the pawls are released during the initial movement of the coin holder.

3. In a vending machine, in combination with a casing, a rotatable magazine, an internal gear connected to said magazine to rotate therewith, a cylindrical coin holder having a peripheral groove therein and a series of coin pockets, a gear on one side of said coin holder meshing with said internal gear on said magazine, ratchet teeth on the other side of said coin holder, a locking pawl coacting therewith, a plunger arranged with its end in the groove of the coin holder to engage a coin held thereby when the plunger is actuated, and means for actuating the plunger, the coin constituting a connector between the plunger and holder and engaging the said pawl whereby the pawl is released during the initial movement of the coin holder and the actuation of said plunger rotates the coin holder.

4. In a vending machine, in combination with a casing, a rotatable magazine, an internal gear connected to said magazine to rotate therewith, a cylindrical coin holder having a series of coin pockets, a gear on one side of said coin holder meshing with said internal gear on said magazine, ratchet teeth on the other side of said coin holder, a locking pawl coacting therewith, a plun-

ger arranged to engage a coin held by the coin holder when the plunger is actuated, and means for actuating the plunger, the coin constituting a connector between the plunger and holder and engaging the said pawl whereby the pawl is released during the initial movement of the coin holder and the actuation of said plunger rotates the coin holder.

5. In a vending machine, in combination with a casing, a rotatable magazine, a gear connected to said magazine to rotate therewith, a cylindrical coin holder having a peripheral groove therein and a series of pockets formed by opposed slot-like notches in the walls of the groove, the front walls of the notches being radial, the rear walls being inclined rearwardly, there being radial slots leading from each pocket to a central opening in the holder, the width of said slots being slightly less than the width of said pockets, a gear on one side of said coin holder meshing with said gear on said magazine, spaced ratchet teeth on the other side of said coin holder, a locking pawl coacting therewith, a plunger arranged with its end in the groove of the coin holder to engage a coin held thereby and means for actuating the plunger, the coin constituting a connection between the plunger and holder whereby the actuation of said plunger rotates said holder, and said coin engaging said pawl to release the same during the initial movement of the coin holder.

6. In a vending machine, in combination with a casing, a rotatable magazine, a gear connected to said magazine to rotate therewith, a cylindrical coin holder having a peripheral groove therein and a series of pockets formed by opposed slot-like notches in the walls of the groove, the front walls of the notches being radial, the rear walls being inclined rearwardly, a gear on said coin holder meshing with said gear on said magazine, ratchet teeth on said coin holder, a locking pawl coacting therewith, a plunger arranged with its end in the groove of the coin holder to engage a coin held thereby and means for actuating the plunger, the coin constituting a connection between the plunger and holder whereby the actuation of said plunger rotates said holder and said coin engaging said pawl to release the same during the initial movement of the coin holder.

7. In a vending machine, in combination with a casing, a magazine, a rotatable cylindrical coin holder having a peripheral groove therein and a series of pockets formed by opposed slot-like notches in the walls of the groove, the front walls of the notches being radial, the rear walls being inclined rearwardly, there being radial slots leading from each pocket to a central open-

ing in the holder, the width of said slots being slightly less than the width of said pockets, driving connections between said coin holder and said magazine, a plunger arranged with its end in the groove of the coin holder to engage a coin held thereby, and means for actuating the plunger, the coin constituting a connection between the plunger and holder whereby the actuation 10 of said plunger rotates said holder.

8. In a vending machine, in combination with a casing, a magazine, a rotatable cylindrical coin holder having a series of peripheral pockets therein there being radial 15 slots leading from each pocket to a central opening in the holder, the width of said slots being slightly less than the width of said pockets, driving connections between said coin holder and said magazine, a plunger 20 arranged to engage a coin held by said coin holder and means for actuating the plunger, the coin constituting a connection between the plunger and holder.

9. In a vending machine, the combination 25 with a casing, of a rotatable magazine, an internal gear secured to said magazine whereby the magazine is rotated therewith, a cylindrical coin holder having a series of peripheral coin pockets, a gear on said coin 30 holder meshing with the said internal gear on said magazine, a ratchet on said holder, a locking pawl coacting therewith, and an actuating plunger, adapted to engage a coin held by said holder, said coin constituting 35 a connector between said plunger and coin

holder, whereby the actuation of said plunger rotates said holder and said coin being adapted to engage the pawl during the initial movement of the holder whereby the pawl is released.

10. In a vending machine, the combination of a casing, comprising base and top sections, a cylindrical magazine having peripheral pockets open at their outer ends, supporting bars on which said magazine is journaled disposed at the sides thereof, the base section of said casing being provided with rests for supporting bars, an internal gear secured to said magazine at one side, a gear journaled on one of said supporting 45 bars in mesh with said last named gear, a coin holder connected with said gear a plunger mounted on such supporting bar and adapted to engage a coin in said holder, the coin constituting a connector between 50 the holder and plunger, a weighted lever mounted on the supporting bar on which 55 said plunger and gear are mounted and having a pin and slot connection with the plunger, and an actuating link pivoted on said lever with its end extended through the casing.

In witness whereof, I have hereunto set my hand and seal in the presence of two witnesses.

HUGH J. KEENAN. [L. S.]
